United States Patent Office

Des. 198,492
Patented June 23, 1964

198,492

VACUUM CLEANER

Salvatore Buda, 1881 Albany Ave., Brooklyn, N.Y.

Filed June 17, 1963, Ser. No. 75,382

Term of patent 14 years

(Cl. D9—2)

FIG. 1

FIG. 2

FIG. 3

FIG. 4

FIG. 5

FIG. 6

FIGURE 1 is a perspective view of a vacuum cleaner, showing my new design;

FIG. 2 is a perspective view thereof viewed from a diagonally opposite position;

FIG. 3 is a top plan view thereof;

FIG. 4 is a side elevational view thereof;

FIG. 5 is an end elevational view thereof taken from the left of FIG. 1; and

FIG. 6 is an end elevational view thereof taken from the left of FIG. 2. Portions of the vacuum cleaner are shown broken away in FIG. 6 for convenience of illustration.

I claim:

The ornamental design for a vacuum cleaner, as shown and described.
